UNITED STATES PATENT OFFICE.

CARL AXEL WILHELM HULTMAN, OF STOCKHOLM, SWEDEN.

SELECTOR SWITCH.

1,415,648.

Specification of Letters Patent.

Patented May 9, 1922.

Application filed December 23, 1918. Serial No. 268,068.

To all whom it may concern:

Be it known that I, CARL AXEL WILHELM HULTMAN, subject of the King of Sweden, residing at Stockholm, Sweden, have invented certain new and useful Improvements in Selector Switches, (for which I have filed application in Sweden, D. No. 4,100/1917, filed December 11, 1917,) of which the following is a specification.

10 The invention relates to automatic telephone exchange system using machine driven switches of a great capacity. Systems of this kind are known in which the switches have a capacity of several thousands of lines (see for instance British specification No. 13362/14). Such switches, however, have heretofore been used chiefly only as numerical selectors or connectors. The object of the present invention is to construct a switch of a great capacity which can be used as a searcher, particularly as a call 20 finder. In this case it is particularly required, that the switch should be capable of establishing connection with the calling line 25 in a relatively short period. To this end, according to the chief feature of the present invention, the movable contact arms of the switch, which are adapted to be set in two difference co-ordinate directions, have no 30 normal position in respect of one direction of movement, the contact arms on release of the switch being restored only in the other direction and stopped in a position opposite to the contact row just left, from which position said arms are started in the first direction by the next call. Upon a call a plurality of call finders are started simultaneously and that one which is next to the contacts of the calling line, establishes the connection.

Fig. 1 shows schematically the principal parts of the call finder and the appertaining circuits. Fig. 2 is a schematic view of the driving device of the call finder. Fig. 3 shows a detail of said device.

In Fig. 1 the switch is shown as a call finder for establishing connections between the subscribers' lines and the operator's position in semiautomatic exchanges or between the subscribers' lines and the junctions in full automatic exchanges. As shown in the drawing, the subscribers' lines *a*, *b* are connected to bare wires *e* common to a number of call finders and extending perpendicularly to the plane of movement of the contact arms *K_u* and *K_v*. The contact field contains in addition to the two branches *a* and *b* of the subscriber's line also two wires *c* and *d* which together with the wires *a* and *b* constitute a number of bundles divided in two main groups *A* and *B*, one of which is arranged above the contact arm *K_u* and the other below the contact arm *K_v*. Each main group contains in this instance fifty vertical rows of ten bundles, the call finder thus having a capacity of 1000 lines.

Upon a call the contact arms first move forwards and backwards between the two main groups of wires, till they find the row of contacts containing the calling line, and then upwards or downwards, till the contact arm in question makes contact with the wires of the calling line.

Figs. 2 and 3 show the operating mechanism of the contact arms. The contact wipers *k* are provided at the upper end of a contact carrier *KB*, which is guided between rollers *R₁* on a carriage *V*, the latter being in turn guided in a horizontal direction on a beam *VB* by means of rollers *R₂*. The contact carrier *KB* is carried by an endless rope *L* fastened to a laterally projecting arm *LA*. The rope is carried round to rope pulleys *LS₁* and *LS₂*, arranged on stationary shafts, and over 3 pulleys *LS₃*, *LS₄*, and *LS₅*, mounted on the carriage, the two latter pulleys being loosely mounted on the same shaft. These two pulleys have actually the same diameter but are shown unequal in the drawing in order that the arrangement of the rope shall appear. The rope runs from the pulley *LS₁* over the pulley *LS₄* and further over the pulleys *LS₃*, *LS₅* and *LS₂* back to *LS₁*. The pulley *LS₁* is keyed to a shaft *DA*, which by means of electromagnetic couplings *MK₁* and *MK₂* (Fig. 1) may be coupled to a driving shaft continuously rotating in the same direction, in such a manner that in one case it is rotated to the left and in another case to the right. The contact carrier is normally locked to the carriage by means of a magnet *VR* provided on the carriage, as shown in Fig. 3. If the clutch *MK₁* is operated, while the magnet *VR* remains inactive, the shaft *DA* rotates to the left the carriage *V* being then also moved to the left as the rope in this case is locked to the carriage by the magnet *VR* and the contact carrier. In a similar way the carriage is caused to move to the right,

if the clutch MK_2 is energized, while the magnet VR remains unoperated. If, on the other hand, the magnet last mentioned is energized simultaneously with the clutch MK_1 or MK_2 respectively the swingably mounted magnet VR is attracted to the beam VB , the carriage being then locked and the contact carrier released. The latter will therefore be moved upwards, if the clutch 10 MK_1 is operated, or downwards, if the clutch MK_2 is operated.

Provided on the carriage are a number of contact wipers KF_1 — KF_6 , Fig. 1, which during the movement of the carriage make contact with a corresponding number of stationary contact bars KS_1 — KS_6 and three contact bars KS_7 , KS_8 and KS_9 , co-operating with three contact wipers KF_7 , KF_8 and KF_9 , respectively provided on the contact carrier 15 K_2 . Mounted on the carriage are further two test wipers KF_{10} and KF_{11} , serving to test the different rows of contacts, when the call 20 finder is moved in a horizontal direction, said wipers then making contact with the test wires f . The movements of the call finder are controlled by a sequence switch SO_s , the contacts of which are designated S_1 — S_{25} . The figures shown close to the contacts indicate those positions of the sequence switch in 25 which the corresponding contacts are closed. This sequence switch may be of any suitable construction similar to that described in the British patent to McBerty 20,839, of 1909.

The call finder operates as follows. When 30 the calling subscriber removes his receiver a circuit 1 is closed through both line branches a , b and through the line relay LR . The latter closes the circuit 2 through a starting relay SR_u (or SR_n , if the subscriber's 35 line is connected to the lower group B) common to ten subscribers. The relay SR_u causes, by closing a circuit 3, the operation of a number of relays F_1R — F_5R , which completes starting circuits 4 for a 40 number of call finders (in the example shown at most 60 call finders), which are started simultaneously. The circuits 3 and 4 contain relays O_1R and O_2R respectively which, in case all call finders should be engaged, close 45 a circuit 5 for a supervisory lamp OLS . The starting circuit 4 contains the clutch magnet MK_1 and all call finders will therefore be moved to the left. The first call 50 finder finding the vertical row of contacts to 55 which the calling line is connected, closes a circuit 6 through one winding of the appertaining test relay LyR_{1u} and the test wiper KF_{10} . The test relay energizes and connects its other winding into a locking circuit 7 60 containing three cut-off relays UR_2 connected in series, which are common to a group of ten call finders having a common impulses register. The circuits 6 for these ten call 65 finders will therefore be opened and consequently no further connection can be estab-

lished in this group of call finders as long as the common impulses register is engaged. At the same time the circuit 6 is directly connected with earth over the contacts 8 and 9 of the relay LyR_{1u} , the group test wires f being thus marked as engaged to the other call finders.

If the call finder does not find the vertical row in question during its movement to the left, the movement is automatically reversed, 70 when the carriage reaches its outer left position, the contact wiper KF_3 then closing a circuit 10 through a shifting relay HR whereby the magnet MK_2 is cut in. The relay HR is then locked over its contact 11 and 75 will therefore remain current carrying, till the relay FR deenergizes, or till the contact 12 is opened in the opposite end position of the carriage when the movement is again reversed.

When relay LyR_{1u} energizes, the circuit 4 is opened and the horizontal movement of the call finders therefore ceases. Further, the relay FR included in said circuit, de-energizes and closes the circuit 13 extending 80 partly through a brake magnet MB and partly through the sequence switch SO_s , which is then moved into its second position in which said circuit 13 is opened. In its second position the sequence switch closes the 85 circuit 14 for three relays UR_1 connected in series, which disconnect the magnetical clutches for the said ten call finders, which are then stopped. At the same time a circuit 15 for the magnet VR and the circuit 16 90 for the clutch magnet MK_1 are closed, whereby the call finder is started upwards.

When the call finder finds the line of the calling subscriber, a circuit 17 is closed 100 through one winding of the test relay LyR_2 ,

which energizes and closes a locking circuit 18 through the other winding and a circuit 19 through the cut-off relay LyR of the subscriber. The subscriber is marked as engaged by the c -wire being connected to earth. The relay LyR disconnects the line relay LR which in turn opens the circuit for the relay SR_u , all call finders, which are still moving, being then stopped. When the test relay LyR_2 energizes, also a circuit 20 is closed 110 partly through the brake magnet MB and partly through the sequence switch SO_s , the latter being then moved into its fourth position, passing the third position. In the 115 fourth position the contact S_{19} is opened, whereby the test wire f is no longer marked as engaged and another calling subscriber in the same vertical row may therefore be searched for by another call finder. At the same time the line branches a , b are connected through the contacts S_{24} , S_{25} to a junction leading for instance to an operator's position, from which the connection is completed in known manner. The sequence switch is 120 then successively moved into its fifth, sixth, 125 seventh and eighth position, the circuit 20 being closed through the contacts S_{24} , S_{25} to a junction leading for instance to an operator's position, from which the connection is completed in known manner. The sequence switch is 130 then successively moved into its fifth, sixth, seventh and eighth position, the circuit 20 being closed through the contacts S_{24} , S_{25} to a junction leading for instance to an operator's position, from which the connection is completed in known manner.

and seventh positions by impulses over the contacts S_4 , S_5 and S_6 in a manner which need not be further explained in this connection. In the seventh position the connection is completed, the contacts S_{14} and S_{20} being then opened and, consequently, the relays UR_1 and UR_2 deenergize, whereby all disengaged call finders of the group of ten call finders in question are released, so that 10 they may be used for another call.

After the end of the conversation the sequence switch is moved into its ninth position by impulses over the contacts S_4 and S_7 . The circuit of the test relay LyR_2 is 15 then opened and owing thereto also the circuit 19 is opened. At the same time the circuit 15 is closed through the magnet VR and the circuit 21 is closed through the shifting relay HR and, further, the circuit 20 22 is completed through a clutch magnet MK_2 , whereby the call finder is started downwards. When the contact carrier reaches its normal position between the main groups A and B, the connection between 25 the contact wipers KF_5 and the contact bar KS_5 is broken, whereby the call finder is stopped. If the call finder had been set in the lower group B, the circuit 21 for the relay HR had not been closed, 30 when the call finder is restored as the contact bar KS_7 only extends over the upper half of the vertical path of the movement and, consequently, the clutch magnet MK_1 should be energized instead of MK_2 and thus 35 the call finder would be started upwards. After the sequence switch has been restored to its initial position, the call finder may be used again for another call.

If the calling subscriber replaces his receiver, before any call finder has reached 40 the vertical row in question, the call finders will be stopped at once.

If, on the other hand, a call finder has 45 reached the vertical row in question or already has moved for a distance into this row, it will continue upwards (or downwards), until it reaches a wire g in its uppermost (or lowermost) position, which is connected to the battery and makes contact with the contact wiper K_4 , when the relay LyR_2 is operated in the same way as already described causing the call finder to be restored.

Having now described and ascertained 55 the nature of my said invention and in what manner the same is to be performed I declare that what I claim is:—

1. In a selector switch having hunting movements in two different co-ordinate directions, means for starting the contact arms from a variable initial position in the first co-ordinate direction upon a call being initiated, means for setting the contact arms in the first co-ordinate direction for the selection of a contact row, and means for set-

ting the contact arms in the second co-ordinate direction for the selection of a particular contact.

2. In a selector switch having hunting movements in two different co-ordinate directions, means for setting the contact arms in the first co-ordinate direction for the selection of a contact row, means for setting the contact arms in the second co-ordinate direction for the selection of a particular contact, means for restoring the contact arms, means for automatically stopping the return movement of the contact arms upon the latter reaching a position opposite to the contact row just left, and means for starting the contact arms from said position in the first co-ordinate direction upon a call being initiated.

3. In a selector switch having hunting movements in two different co-ordinate directions, means for starting the contact arms from a variable initial position in the first co-ordinate direction for the selection of a contact row, a reversing device for automatically controlling the movement of the switch to one or the other side in said co-ordinate direction, and means for setting the contact arms in the second co-ordinate direction for the selection of a particular contact.

4. In a selector switch having hunting movements in two difference co-ordinate directions, means for starting the contact arms from a variable initial position in the first co-ordinate direction for the selection of a contact row, a reversing device for automatically controlling the movement of the switch to one or the other side in said co-ordinate direction, means for setting the contact arms in the second co-ordinate direction for the selection of a particular contact, means for restoring the contact arms, and means for automatically stopping the return movement of the contact arms upon the contact arms reaching a position opposite to the contact row just left.

5. In a selector switch having hunting movements in two different co-ordinate directions, means for setting the contact arms in the first co-ordinate direction for the selection of a contact row, a reversing device for automatically controlling the movement of the switch to one or the other side in said co-ordinate direction, means for setting the contact arms in the second co-ordinate direction for the selection of particular contacts, means for restoring the contact arms, and means for automatically stopping the return movement of the contact arms upon the contact arms reaching a position opposite to the contact row just left.

6. In a selector switch having hunting movements in two different co-ordinate directions, means for setting the contact arms

- in the first co-ordinate direction for the selection of a contact row, a reversing device for automatically controlling the movement of the switch to one or the other side in said co-ordinate direction, means for operating the reversing device to reverse the movement upon the contact arms reaching their end position in the said co-ordinate direction, means for setting the contact arms in the second co-ordinate direction for the selection of a separate contact, means for restoring the contact arms, and means for automatically stopping the return movement of the contact arms upon the contact arms reaching a position opposite to the contact row just left.
7. In a selector switch having hunting movements in two different co-ordinate directions, means for starting the contact arms from a variable initial position in the first co-ordinate direction for the selection of a contact row, a reversing device for automatically controlling the movement of the switch to one or the other side in said co-ordinate direction, means for operating the reversing device to reverse the movement in both end positions of the contact arms, and means for setting the contact arms in the second co-ordinate direction for the selection of a separate contact.
8. In a selector switch having hunting movements in two different co-ordinate directions, a movable switch member carrying contact arms, fixed line contacts arranged in two main groups provided one on each side of said switch member, means for starting the contact arms from a variable initial position in the first co-ordinate direction for the selection of a row of contacts, and means for starting the contact arms to either side in the second co-ordinate direction for the selection of a particular line contact in one or the other of said main groups.
9. In a selector switch having hunting movements in two different co-ordinate directions, a movable switch member carrying contact arms, fixed line contacts arranged in two main groups provided one on each side of said switch member, means for setting the contact arms in the first co-ordinate direction for the selection of a contact row, a reversing device for automatically controlling the movement of the switch to one or the other side in said co-ordinate direction, means for setting the contact arms to one or the other side in the second co-ordinate direction for the selection of a particular line contact, means for restoring the contact arms, and means for automatically stopping the return movement of the contact arms upon the contact arms reaching a position opposite to the contact row just left.
10. In a selector switch having hunting movements in two different co-ordinate directions, a movable switch member carrying contact arms, fixed line contacts consisting of bare wires extending perpendicularly to the plane of movement of the contact arms and arranged in two main groups provided one on each side of said switch member, means for setting the contact arms in the first co-ordinate direction for the selection of a contact row, a reversing device for automatically controlling the movement of the switch to one or the other side in said co-ordinate direction, means for operating the reversing device to reverse the movement in either end position of the contact arms, means for setting the contact arms to one or the other side in the second co-ordinate direction for the selection of a particular line contact, means for restoring the contact arms, and means for automatically stopping the return movement of the contact arms upon the contact arms reaching a position opposite to the contact row just left.
11. In a selector switch having hunting movements in two co-ordinate directions, fixed line contacts arranged in rows, means for starting the contact arms from a variable initial position in the first co-ordinate direction for the selection of a contact row, means for setting the contact arms in the second co-ordinate direction for the selection of a particular contact, and means for marking a contact row as engaged as soon as the switch has found the contact row to which the calling line is connected.
12. In a selector switch having hunting movements in two co-ordinate directions, fixed line contacts arranged in rows, means for starting the contact arms from a variable initial position in the first co-ordinate direction for the selection of a contact row, means for setting the contact arms in the second co-ordinate direction for the selection of a particular contact, means for marking a contact row as engaged as soon as the switch has found the contact row to which the calling line is connected, and means for marking said contact row as disengaged as soon as the switch has found the contact of the calling line.
